[57] ABSTRACT

An excavator boom has attachment means formed on opposite ends thereof for attachment to a vehicle and to a work implement. The boom comprises a pair of continuous and uninterrupted upper and lower plates and a pair of side plates, all secured together by four continuous welds to form a box section throughout the length of the boom. The boom is generally V-shaped and has a third attachment means formed at the apex thereof. During fabrication of the boom, the various plates and attachment means are positioned in suitably arranged fixtures and are tack welded together. The boom is then placed on each of its sides for final welding purposes.

BOOM CONSTRUCTION AND METHOD FOR MAKING SAME

BACKGROUND OF THE INVENTION

Implement carrying booms for hydraulic excavators and the like are normally fabricated from a plurality of steel plates secured together by a multiplicity of transverse and longitudinal welds. The plates are normally roll formed to provide a back-up ridge for the longitudinal welds (see FIG. 8 of applicant's drawings) which gives rise to various stress problems discussed in applicant's copending U.S. application Ser. No. 348,926, filed on Apr. 9, 1973 for "Stress-Relieved Weldment for Box Sections". Stress concentrations are particularly occasioned at a mid-portion of the boom whereat cast members are secured thereto to provide attachment means for one end of a hydraulic cylinder which is further attached to a vehicle for boom raising and lowering purposes.

SUMMARY OF THIS INVENTION

An object of this invention is to provide a boom construction which exhibits a high degree of structural integrity and an economical method for expeditiously making the same. The boom comprises attachment means formed on opposite ends thereof, a pair of continuous and uninterrupted upper and lower plates and side plates secured to the upper and lower plates by four continuous weld means extending substantially the full length of the boom. The boom is fabricated by positioning the various plates and attachment means in suitably arranged gigs and fixtures and by initially tack welding them together. The boom is then laid on each of its sides for the final welding operation.

BRIEF DESCRIPTION OF THE DRAWINGS

Other objects of this invention will become apparent from the following description and accompanying drawings wherein:

FIG. 1 is a side elevational view of a hydraulic excavator employing a boom of this invention theron;

FIG. 2 is an enlarged, side elevational view of the boom;

FIG. 3 is an enlarged sectional view taken in the direction of arrows III-III in FIG. 2;

FIG. 4 is an enlarged sectional view taken in the direction of arrows IV-IV in FIG. 2;

FIG. 5 is a view similar to FIG. 4 but illustrating a prior art weldment;

FIG. 6 is an enlarged cross sectional view taken in the direction of arrows VI-VI in FIG. 2;

FIG. 7 is a view similar to FIG. 3 but showing attachment structure exploded with the welds removed therefrom; and

FIG. 8 is an enlarged top plan view of one end of the boom, taken in the direction of arrows VIII-VIII in FIG. 2.

DETAILED DESCRIPTION

FIG. 1 illustrates a hydraulic excavator 10 having a first end of a boom 11 of this invention pivotally mounted thereon by a first pivot means 12. The second end of the boom is attached to a work implement, such as a bucket 13, by a second pivot means 14 and intermediate stick 15. The boom is generally V-shaped and has a pair of first double-acting hydraulic cylinders 16

(one shown) each attached to an apex thereof by a third pivot means 17.

The head end of the cylinders are each pivotally attached on the vehicle by a fourth pivot means 18 to facilitate raising or lowering of the boom under control of the operator. A second double-acting hydraulic cylinder 19 has its head end mounted on an upper side of the boom by a fifth pivot means 20 and its rod end is attached to the upper end of stick 15 by a sixth pivot means 21. A third double-acting hydraulic cylinder 22 is pivotally interconnected between an upper end of stick 15 and bucket 13, through suitable linkage means 23, to selectively pivot the bucket on the stick.

Referring to FIG. 2, boom 11 comprises a pair of continuous and uninterrupted upper and lower plates 24 and 25, respectively, and a pair of side plates 26 secured thereto. The structurally integrated plates form a box section substantially throughout the full length of the boom. Each side plate 26 comprises a pair of plates 26 and 27 secured together at a transverse weld 28 (FIG. 3).

The weld is backed-up throughout its length by a flat member 29 disposed interiorly of the boom. The boom's structural integrity is not adversely affected by such a weld. In particular, the major stresses imposed on the boom during operation thereof occur adjacent to its apex, at attachment means 17 (FIG. 1).

As further shown in FIG. 3, each plate 26 may have a thickness T_1 (e.g., 1 in.) which is greater than the thickness T_2 (e.g., $\frac{3}{4}$ in.) of each plate 27. The forward end of each plate 26 is preferably machined to form a taper throughout a forward portion L of its length to match the thickness of a respective, co-planar plate 27. Such a construction substantially reduces the overall weight of the boom without adversely affecting its bending strength.

Referring to FIG. 4 the upper, lower and side plates are secured together by four continuous weld means 30, each securing a lateral side of one of the upper and lower plates to a respective one of the side plates. As shown, each weld means 30 has a generally V-shaped cross section terminating at an apex thereof at an L-shaped angle bar 31 which functions as a back-up means for the weld. Such a stress relieved weldment is fully disclosed in applicant's above referenced U.S. application Ser. No. 348,926. In particular, FIG. 5 illustrates a prior art weldment wherein a pair of plates 25' and 26' are secured together by a weld 30' which terminates at its apex at a rolled section 31' formed on plate 25'.

Since the rolled section is formed integrally with the plate, it cannot be selectively sized or positioned to accommodate manufacturing and assembly tolerances a and b . As a result, weld "blow-through" may occur whereby a poor weldment is formed to adversely affect the overall structural integrity of the boom. In contrast thereto, angle bar 31 (FIG. 4) can be suitably sized and positioned to provide a zero clearance between the angle bar and side plate 26 and a precisely controlled clearance C at the apex or root of weld 30 to assure the formation of structurally sound weldments.

Referring to FIGS. 1, 6 and 7, pivot means 17 comprises an attachment means including a pair of bell castings 32 each extending through an annular opening 33 formed through a respective side plate 26 and secured thereto by an annular weld 34. An annular first flange 35 is formed on each bell casting to extend radi-

ally outwardly therefrom to abut inner surface portions of plate 26 to precisely position the bell casting thereon and to also provide a weld back-up means thereat for weld 34. An annular second flange 36 extends axially inwardly from each bell casting to underlie a respective end of an intermediate cylindrical connecting member 37. A pair of annular welds 38 secure the opposite ends of the connecting member to the bell castings.

Referring to FIGS. 1 and 8, first pivot means 12 comprises an attachment means or yoke at the first end of the boom having a pair of bearing bushings 39 secured thereon for pivotally mounting the boom on the frame of vehicle 10. Referring to FIGS. 1 and 2, second pivot means 14 comprises an attachment means or casting 40 welded on the second or forward end of the boom for pivotal attachment to stick 15. As further shown, fifth pivot means 20 comprises an attachment means or casting 41 secured on upper plate 24 for pivotally attaching the head end of cylinder 19 thereon.

METHOD OF FABRICATION

Boom 11 is fabricated by first flame cutting and shaping upper, lower and side plates 24-26. Openings 33 (FIG. 7) are formed through the side plates and castings 32 and member 37, presecured together by welds 38, are suitably mounted therein. The vertical legs of preshaped angle bars 31 are then tack welded to the side plates in a suitable fixture whereby each leg projects slightly beyond a lateral end of a side plate to precisely set clearance C (FIG. 4) for subsequent formation of the weld grooves for welds 30.

Lower plate 25 is then mounted in a suitable fixture, in its FIG. 2 position. The side plates, having castings 32 and member 37 tack welded thereto, are then accurately positioned on the bottom plate 25 and tack welded thereto. Top plate 24 is then positioned on the side plates and tack welded thereto along with castings 32 and 41 and bushings 39.

The tack welded sub-assembly is then turned on a first side thereof to complete the exposed major welds, including a weld 34 and two of the four continuous welds 30 securing the upper, lower and side plates together. The boom is then turned over onto its second, opposite side and a similar welding operation is effected thereon to complete the major welds. The boom is then mounted on excavator 10 (FIG. 1) and attached to the various cylinders and stick 15.

I claim:

1. A generally V-shaped boom comprising attachment means on a first end of said boom 50

adapted for attachment on a vehicle, a pair of continuous and uninterrupted upper and lower plates and side plates each extending substantially the full length of said boom between the first and second ends thereof to form a box section, four continuous weld means each securing a lateral side of each one of said upper and lower plates to a respective one of said side plates and second attachment means disposed at an apex of said boom comprising a pair of annular castings each disposed in an opening formed through a respective side plate and an intermediate cylindrical connecting member secured between said castings.

2. The boom of claim 1 wherein said attachment means pivotally mounts said boom on a frame of an excavator and further comprising another attachment means on a second, opposite end of said boom pivotally attached to a work implement.

3. The boom of claim 1 further comprising an L-shaped angle bar disposed interiorly of said boom and secured to each of said weld means at an apex thereof, said weld means and a respective angle bar being co-terminus at least substantially throughout the length of said boom.

4. The boom of claim 1 wherein each of said side plates comprises first and second co-planar plates and a weld, disposed transversely relative to said side plates, securing said first and second plates together.

5. The boom of claim 4 further comprising a flat back-up member secured to said weld and abutting said first and second plates, interiorly of said boom.

6. The boom of claim 4 wherein said first plate has a wall thickness greater than the thickness of said second plate, an end portion of said first plate adjacent to said second plate being tapered-down to substantially match the wall thickness of said second plate.

7. The boom of claim 1 further comprising an annular first flange formed on each of said castings to extend radially outwardly therefrom to abut inner surface portions of a respective side plate.

8. The boom of claim 7 further comprising an annular weld securing each of said castings to a respective said plate at said first flange.

9. The boom of claim 7 further comprising an annular second flange formed on each of said castings to extend axially inwardly to underlie a respective end of said connecting member and an annular weld securing each of said castings to a respective end of said connecting member at said second flange.
